UNITED STATES PATENT OFFICE.

ROBERT H. ANDERSON, OF SAN DIEGO, CALIFORNIA, ASSIGNOR TO RUTH B. ANDERSON,
OF SAN DIEGO, CALIFORNIA.

WALL-BED.

1,074,592.

Specification of Letters Patent. Patented Sept. 30, 1913.

Application filed December 19, 1910. Serial No. 597,976.

To all whom it may concern:

Be it known that I, ROBERT H. ANDERSON, a citizen of the United States, and a resident of San Diego, in the county of San Diego and State of California, have invented new and useful Improvements in Wall-Beds, of which the following is a specification.

My invention relates to wall or folding beds for dwellings, hotels, apartment houses and like places where a maximum of accommodation is required in a minimum of space, and the same being mounted upon a pivoted panel may be concealed in an opening or recess in the wall when the bed is not in use and which is turned in a relative position in the room or elsewhere when needed.

The objects of the invention are, to provide a simple, economical and easily operated wall bed, further to provide a bed that will only require a small amount of wall space when closed and that may be used in two different rooms when desired and further requires no springs or weights to facilitate its folding and further that the wall space may be used as a closet from either side while the bed is out for use as well as when it is closed.

With these and other objects in view my invention consists of certain novel features of construction, combination and arrangement of parts as will be hereinafter described and particularly set forth in the appended claims, reference being had to the accompanying drawings, and to the characters of reference thereon, which form a part of this specification, in which:

Figure 1 is a vertical section of my bed showing in full lines the bed closed and indicating by dotted lines its position when open ready for use, Fig. 2 is a plan view thereof showing the wall in section, Fig. 3 is a side elevational view showing the bed in a closed position on the reverse side of the wall to that of Fig. 1, and Fig. 4 is a front elevational view showing the bed closed and mounted on the panel.

Similar characters of reference refer to similar parts throughout the several views.

In the drawings, numeral 1 represents the floor line, 2 the wall in which the bed is hung, 3 a panel upon which the bed is mounted, 4, 5, and 6 hinged doors or closures for the space in the wall, 7 the bed frame, 8 a stationary head-board upon which the frame is mounted, 9 a swing rod, 10 a

thrust rod, 11 an inner support, 12 an outer support.

In the wall 2 where the bed is to be located there is provided a space a little wider than the bed, which is inclosed on one side by means of double doors 5 and 6. On the other side adapted to inclose approximately one-half of the space is another door 4. The rest of said space is provided with a centrally pivoted panel or door 3. Upon this panel 3 there is substantially mounted on one side a stationary head-board 8 by means of bolts 8^a. On the one side the bed extends past the panel about one-half its width. On the head-board 8 are substantially pivoted rods 9, one on each side, which extend downward and connect pivotally with the bed frame at 9^a. In the lower end of said head-board are pivotally mounted thrust rods 10 which extend upwardly and pivotally connect with the lower side of bed frame 7 at point 10^a near the end of said bed frame. These thrust rods 10 are for the purpose of thrusting the bed downward and away from the panel when it is being closed, and for guiding and holding it away from the panel when being opened. The bed is suspended and swings on rods 9, thus providing a very simple means of raising and lowering it and doing it in such a manner that a minimum of wall space is required for it. The bed frame 7 is also provided with inner and outer supports 11 and 12 which are pivotally mounted thereon and adapted to swing into the wall space when the bed is closed as shown in Fig. 1 and to substantially support the bed when it is down, as shown by dotted lines in Fig. 1.

When it is desired to use the bed on the opposite side of the wall from that shown in Fig. 1 the door 4 is opened and the panel on which the bed is mounted is swung to the opposite side, thus placing the bed in the position shown in Fig. 3 where it may be lowered for use.

Though I have shown and described a particular construction, and arrangement, I do not wish to be limited to such construction and arrangement, but desire to include substantially the principles involved and the construction and arrangement as described in the appended claims.

It will be readily seen that with this construction and the method of mounting there is provided a simple, economical and easily

100

95

105

110

operated wall bed which may be used on either side of the wall, thus being adapted for two different rooms, that the wall space may be used as a closet from either side 5 when the bed is lowered for use as well as when it is closed; that the method of hanging the bed frame upon the head-board provides a simple construction which thrusts the bed outward when down, thus minimizing the wall space required.

Having thus described my invention, what I claim as new and desire to secure by Letters Patent, is:—

1. The combination with a wall provided 15 with an opening therein, of a panel centrally and vertically pivoted to one side of the middle of said opening, adapted to close approximately one-half of said opening, a head board of a bed frame secured to said 20 panel so that one of its ends extends past said panel and along the wall on the panel side of said opening approximately one-half of its width when the panel is turned so that said headboard is out of said opening, a door hinged to the opposite side of 25 said opening for closing its remaining portion and to allow the extended portion of said head board to pass through said opening when revolved with said panel, and a 30 bed frame pivotally mounted on said head board.

2. The combination with a wall provided 35 with an opening therein, of a panel centrally and vertically pivoted to one side of the middle of said opening adapted to close approximately one-half of said opening, a head board of a bed frame secured to said panel so that one of its ends extends past said panel and along the wall on the 40 panel side of said opening approximately one-half of its width when the panel is turned so that said headboard is out of said opening, a door hinged to the opposite side of said opening for closing the remaining 45 portion and to allow the extended portion of said head board to pass through said opening when revolved with said panel, tension rods pivotally mounted at their one ends near the top of said head board, a bed 50 frame pivotally mounted on the other ends of said tension rods, thrust rods pivotally mounted at their one ends near the bottom of said head board and the other ends there-

of pivotally mounted on said bed frame in front of and below the pivotal mountings of 55 said tension rods, and a plurality of pivotally mounted supports adapted to support said bed frame when down.

3. The combination with a receptacle provided with an opening therein and a door hinged at the one side thereof closing approximately one-half of said opening into said receptacle, of a panel centrally and vertically pivoted at its upper and lower ends on the upper and lower sides of 65 the receptacle, closing the remainder of the opening into said receptacle when parallel therewith, a head board of a bed firmly mounted on said pivoted panel so that when said panel is turned in one direction one 70 end projects along the wall beyond said pivoted panel and when reversed with said panel it passes through the side of the opening closed by said hinged door into the portion of said receptacle closed by said 75 hinged door.

4. The combination with a receptacle provided with an opening therein and a door hinged at the one side thereof closing 80 approximately one-half of said opening into said receptacle, of a panel centrally and vertically pivoted at its upper and lower ends on the upper and lower sides of the receptacle closing the remainder of the opening into said receptacle when parallel 85 therewith, a head board of a bed firmly mounted on said pivoted panel so that when said panel is turned in one direction one end projects along the wall beyond said pivoted panel and when reversed with said 90 panel it passes through the side of the opening closed by said hinged door into the portion of said receptacle closed by said hinged door, a bed frame pivotally mounted on said head board and adapted to be swung 95 vertically, thrust rods connecting said head board and said frame adapted to control the inward swing of said frame and supports pivotally mounted on said frame.

In witness whereof, I hereunto subscribe 100 my name in the presence of two subscribing witnesses.

ROBERT H. ANDERSON.
